UNITED STATES PATENT OFFICE.

WILLIAM T. EVANS, OF MITCHELL, NEBRASKA.

LANTERN.

Application filed May 15, 1922. Serial No. 561,000.

To all whom it may concern:

Be it known that I, WILLIAM T. EVANS, a citizen of the United States, residing at Mitchell, in the county of Scotts Bluff and 5 State of Nebraska, have invented new and useful Improvements in Lanterns, of which the following is a specification.

This invention relates to a lantern, the principal object of the invention being to 10 provide means for supporting an electric lamp and a battery for supplying current to the same and providing the supporting means with straps so that the device can be attached to the person, thus leaving both 15 hands free and to provide the device with legs so that it can be placed in upright position, the same as an ordinary lantern.

Another object of the invention is to provide means for adjusting the lamp in the 20 support so that the rays can be cast in different directions and to provide an easily operable switch for controlling the flow of current to the lamp.

This invention also consists in certain 25 other features of construction and in the combination and arrangement of the several parts, to be hereinafter fully described, illustrated in the accompanying drawings and specifically pointed out in the appended 30 claims.

In describing my invention in detail, reference will be had to the accompanying drawings wherein like characters denote like or corresponding parts throughout the sev- 35 eral views, and in which:—

Figure 1 is a view showing the invention strapped to a person.

Figure 2 is a side view of the device itself.

Figure 3 is a rear view.

Figure 4 is a section on line 4—4 of Figure 3.

Figures 5, 6, 7, 8, 9 and 10 are detail views.

In these views 1 indicates a casing which has its front sloping upwardly and outwardly, as shown at 2, to a point adjacent the top where the front slopes inwardly to the top, as shown at 3. An opening 4 is 45 made in the center of the front, the walls of which being pressed inwardly to form an annular depression 5 around the opening. One end of the casing is provided with a hinged door 6 and with a slide 7, the slide 50 controlling communication to the bottom part of the casing while the door controls

communication to the top of the casing. Supports 8 are arranged in the casing, the said supports being arranged to receive a battery 9 which is located in the upper part 60 of the casing and is adapted to be inserted through the door. Spring means 10 are arranged to hold the battery firmly in position and thus prevent rattling of the parts. A lamp 11 is arranged in the opening 4, said 65 lamp including a body 12 which has a flaring portion to engage the depression 5 and the front of which is closed by a lens 13. The rear part of the lamp carries a block 14, the inner face of which is provided with 70 a socket 15 to receive an ordinary electric bulb 16, the contacts 17 for the bulb passing through the block, the projecting ends being suitably formed to receive the ends of the conductors 18. These conductors are 75 connected with the battery and with a switch 19. The body of the lamp is covered with suitable flexible material 20, portions of which engage the depressed walls around the opening and thus make a noiseless connection between the lamp and said walls. The block 14 carries the spring clamp 21 80 which is adapted to engage the cranked rod 22 which has its ends passing through the ends of the casing. These projecting ends are provided with handles 23 so that the rod can be rocked to move the lamp and thus direct the rays thereof upwardly or downwardly or horizontally. A slot 24 is formed in the front of the casing, near the 85 bottom thereof, and the switch handle 25 projects from this slot. By sliding this handle in the slot the switch will be operated to open or close the circuit from the lamp to the battery. The conductors are made long enough so that the lamp can be removed 90 from the casing, by pulling the clamp from the cranked rod. This will permit a new bulb to be inserted or inspection of the lamp. Vertically extending projections 26 are secured to the back of the casing at the sides thereof and a cross bar is secured to the back with its ends projecting from the sides of the casing. Buttons 28 are carried 95 by these projecting ends for receiving the eyes formed in straps 29 which are adapted to be passed around the body of a person, as shown in Figure 1, to secure the device on the person's chest. Legs 30 are placed 100 on the top of the casing so that the casing can be reversed with the legs engaging a surface to hold the device in upright posi- 105 110

tion. The projections 26 act to space the device from the person and thus reduce movement of the same due to the movement of the body. The peculiar formation of the 5 front of the casing will prevent the light from entering the eyes of the user and thus blinding him.

From the above it will be seen that when the device is strapped to the body of a person 10 the eyes will be shaded from the light and the current to the lamp can be easily turned on or off by the switch at the front of the casing. The rays of light can be directed downwardly or upwardly as well as 15 horizontally by means of the cranked rod and the lamp can be removed from the casing when desired. The switch parts can be inspected through the opening closed by the slide and the battery can be inserted and re- 20 moved through the opening closed by the door.

A handle 31 is placed on the top of the casing, the handle engaging its supporting brackets so that it will be held in any position 25 by friction. I may also place a receiver 32 in the device for holding an extra supply of lamp bulbs.

It is thought from the foregoing description that the advantages and novel features 30 of my invention will be readily apparent.

I desire it to be understood that I may make changes in the construction and in the combination and arrangement of the several parts, provided that such changes fall with 35 in the scope of the appended claims.

What I claim is:—

1. A device of the class described compris-

ing a casing having an opening in its front face, a lamp body located in said opening, a cranked rod passing through the casing and having a handle on its projecting end, a spring clamp on the lamp body engaging the crank of said rod so that the lamp body can be tilted in the opening, a battery in the 45 casing, a circuit from the battery to the lamp, a switch in the circuit, the switch handle projecting from the front of the casing and doors for permitting access to the casing.

2. A device of the class described comprising a casing having an opening in its front face, a lamp body located in said opening, a cranked rod passing through the casing and having a handle on its projecting end, a spring clamp on the lamp body engaging the crank of said rod so that the lamp body can be tilted in the opening, a battery in the 50 casing, a circuit from the battery to the lamp, a switch in the circuit, the switch handle projecting from the front of the casing, 55 doors for permitting access to the casing and a harness for connecting the device to the body of the person.

3. A device of the class described comprising a casing; having an upwardly and outwardly sloping front, said front having an opening therein, a lamp body located in the opening, means manually operated for tilting the body in the opening, a battery in the 60 casing, a circuit connecting the same with the lamp and switch means for controlling the circuit.

In testimony whereof I affix my signature.
WILLIAM T. EVANS.
